DISPLAY CONTAINER

Samuel Braun, Rye, N.Y., assignor to B.C.N. Design Products, Inc., Amityville, N.Y., a corporation of New York

Filed Mar. 7, 1966, Ser. No. 1,322

Term of patent 14 years

(Cl. D58—12)

FIG. 1

FIG. 2

FIG. 3

FIG. 4

FIG. 6

FIG. 5

FIG. 1 is a top plan view of the display container, showing my new design;

FIG. 2 is a side elevational view thereof taken from the right hand side of FIG. 1;

FIG. 3 is an end elevational view thereof taken from the upper end of FIG. 1;

FIG. 4 is a bottom plan view thereof;

FIG. 5 is an end elevational view thereof taken from the lower end of FIG. 1; and

FIG. 6 is a three-quarter perspective view thereof with the container shown in open display position.

The dominant features of my design reside in the portions shown in full lines.

I claim:

The ornamental design for a display container, as shown and described.
